(57) **CLAIM**

The ornamental Design for a camouflage tire and wheel assembly, as shown and described.

DESCRIPTION

The sole FIGURE is a side elevational view of a camouflage tire and wheel assembly showing our new design.

In the drawings, the broken lines defining the sidewall and inner bead and the wheel are for illustrative purposes only and form no part of the claimed design. The drawings are lined for color. The areas of the drawing shaded with stippling represent areas having no color.
